UNITED STATES PATENT OFFICE

HENRY THOMAS, OF RIDLEY PARK, PENNSYLVANIA, ASSIGNOR TO SUN OIL COMPANY, OF PHILADELPHIA, PENNSYLVANIA, A CORPORATION OF NEW JERSEY

OIL CRACKING APPARATUS

Application filed June 8, 1927. Serial No. 197,283.

The present invention relates to those apparatus for racking hydrocarbon oils which comprise a tube, or series of tubes, for heating oil under high pressure to a temperature considerably above a minimum cracking temperature (say 800-900° F.) and a chamber, in series with the tube or tubes, in which the cracking under the same high pressure is completed and from which the cracked hydrocarbons escape into towers wherein the superatmospheric pressure is greatly reduced or removed and wherein the lighter cracked hydrocarbons are separated from the heavier cracked hydrocarbons. Such chambers are differently designated as cracking tanks, soaking drums or reaction chambers. The term "reaction chamber" is apt in that it defines whatever action may occur in the tank or drum. The hydrocarbons undergoing cracking are usually introduced at or near one end of the chamber and escape from or near the other end of the chamber through a valve, which regulates the rate of outflow and also maintains the proper pressure on the chamber and the heating and cracking tubes.

Because of the high pressure and high temperature that are maintained in the chamber, and because, also, of the factor of safety which the high temperature requires and the fatigue of the metal, these chambers are limited in size. This limits the size of the unit of which the chambers forms a part. The capacity of the whole cracking unit is therefore limited.

It is also not possible, with such a unit, to continuously carry on the cracking operation for longer than a limited time. The reason for this is that carbon, which is a resultant product of the cracking, gradually settles out in the chamber and ultimately accumulates to such an amount as to necessitate the stoppage of the operation and the cleaning out of the chamber. The length of the run, therefore, depends very largely on the carbon-carrying capacity of the chamber, and the size of the latter is limited by the factors above explained.

It has been proposed to provide a plurality of reaction chambers to be fed from a

common series of heating and cracking tubes. This arrangement would obviously enable the length of the run to be multiplied proportionately to the increase in number of chambers; or the capacity of the unit could be multiplied to the same degree with no increase in length of run; or both the capacity of the unit and the length of the run could be increased.

It is a fact, however, that it is difficult to attempt to yoke a plurality of reaction chambers to a single heating and cracking pipe or pipe series. The mere provision of branch pipes with valves to control the flow has been tried and found troublesome, uncertain and dangerous. It should be borne in mind that the mixture of hydrocarbons undergoing cracking, as it leaves the cracking tube and enters the reaction chamber, is, if heated to, or even considerably below, 900° F., above its critical temperature and therefore in gas phase, and even though heated to below its critical temperature and therefore largely in liquid phase, the mixture flows into the reaction chamber at high speed and under very high temperature and its flow cannot be controlled by the many obvious expedients which would be successful in controlling fluid flow under lower temperatures and at lower velocities.

In the attached drawings I have shown a construction whereby the flow can be accurately and safely controlled and which is operated successfully on a commercial scale.

Fig. 1 is a plan view of the apparatus. 85

Fig. 2 is an end view.

Fig. 3 is a detail view of the distributing box.

Fig. 4 is an end view of a modification.

Fig. 5 is a perspective view of the distributing box shown in Fig. 4.

The discharge end, or an extension from the discharge end, of a cracking tube *a* (which may be in series with a preheating tube, not shown) is connected to a special junction box 95 fitting *b*. The form of the box shown approximates that of a cube. Preferably (if only two reaction chambers are provided) it is a six-sided box, one end of which is connected with pipe *a*, while two adjacent sides 100

are connected with pipes *c* and *d*, which are connected respectively with the end portions of two reaction chambers *h* and *i*, extending horizontally and in parallelism with each other and with the inlet pipe *a*. The pipes *c* and *d* extend at equal angles to a vertical plane passing through the axis of the inlet pipe *a*, which is midway between the two chambers. In the drawings, pipes *c* and *d* are shown as extending at angles of approximately 45° to the vertical plane; but successful operation does not preclude a substantial variation from this angle. Since the chambers are very heavy and are fixed in their position, the arrangement shown and described provides for the necessary movement due to expansion and contraction as well as for the equal division of the hydrocarbon stream.

Box *b* is also provided with three plugs *e*, *f* and *g* located respectively on the end of the box opposite inlet pipe *a* and on the sides of the box opposite outlet pipes *c* and *d*.

The box need not be of the shape shown even if connections are provided to only two reaction chambers and would be of different shape if more than two reaction chambers were used.

The high velocity of the entering oil is not only no hindrance to successful operation of the distributing device shown but is probably necessary to its successful operation. The hydrocarbon stream, traveling through pipe *a* at a velocity (say) of 8 to 10 feet per second, strikes the dead end of the box fitting and divides itself automatically into two streams of equal volume that shoot through the pipes *c* and *d* into the chambers *h* and *i*.

This operation is more or less dependent upon the provision that I have made for controlling the outflow of hydrocarbons (in whatever condition they are, whether liquid and vapor, or gas, when they leave the reaction chamber). Each outlet line is equipped with a special type of valve. After a reaction chamber has been in use for some time, the valve becomes slogged with carbon near the outlet from the chamber, and it is necessary to provide a boring device for removing the deposit while the system is in operation and under pressure. Such boring devices are known and in use. In the structure shown in the drawings, the outlet valves are so positioned as to allow two chambers to be placed side by side, with a comparatively small space between them, and yet leave the necessary room for the boring-out equipment, which must of necessity occupy considerable space. If only two reaction chambers are used, it is possible to place the outlet lines and the boring-out equipment on the opposite sides of two chambers. If, however, more than two chambers are placed side by side, as, for instance, where there are two units with two chambers each, or two units with three chambers each, obviously only two

of the outlet lines could be placed on the outside.

In my construction the outlet pipe sections *m* and *n*, equipped with special valves *o* and *p*, are placed on opposing sides of the reaction chambers *h* and *i* somewhat above a horizontal plane intersecting the axes of the chambers, and extend therefrom at relatively sharp angles to the horizontal and at relatively wide angles to the vertical. The two outlet pipe sections also extend along different, but not widely spaced-apart, vertical planes extending perpendicularly to the axes of the reaction chambers. Diverging from pipes *m* and *n*, and constituting extensions thereof, are two pipes *r* and *s*, which communicate with a common pipe *t* leading to the tower or towers (not shown) for separating the gasoline constituents from the heavier constituents of the cracked mixture of hydrocarbons. Pipes *m*, *n* are equipped with pressure gauges *v*, *v*, at substantially distances from valves *o* and *p* and from the union of such pipes with pipe *t* and preferably, but not necessarily, midway between said valves and pipe *t*. Such pressure gauges, or equivalent devices, function practically as orifice meters to measure the pressure drop on the lines and indicate to the operator the relative flow through the lines, so that he can adjust valves *o* and *p*, when necessary, to equalize the flow from the chambers.

The reaction chambers should be equipped with pressure gauges *w*, *w*, which can be used in conjunction with pressure gauges, *v*, *v*, to show the conditions in the inflow lines to the chambers and outflow lines from the chambers to determine whether they are becoming clogged with carbon and thus obstructing the free flow of hydrocarbons into the chambers.

The boring-out device *y*, *y*, are positioned to engage the ends of pipe sections *m* and *n*, and extend in alignment therewith, so that each is in a position to be conveniently operated without interference with the other boring-out device.

Without provision for measuring and regulating the outflow from the two reaction chambers, the conditions of volume, rate of travel, pressure and other factors within the two chambers may be so unequal and uncertain that the described operation of the feed to the chambers, and particularly the substantially equal distribution of the flow thereto, would not occur, notwithstanding the tendency of the special box fitting construction to effect such equal division. The described construction, if operated with reasonable care, creates and maintains substantially the same conditions in the two chambers and meets all the requirements of a cracking unit with multiple reaction chambers.

It will be noted that, aside from the necessary valve at the outlet end of each reaction chamber, which is just as indispensable when

the unit comprises a single reaction chamber, the construction is capable of operation without the use of any other valves whatever. This feature is of great importance, as such 5 valves, although they have been deemed necessary in multiple reaction chamber constructions, are a main source of the trouble, uncertainty and danger incident, heretofore, to the attempted provision of multiple reaction 10 chambers.

In Figs. 4 and 5 is shown a preferred adaptation of my invention to a set of three reaction chambers 11, 12 and 13. The arrangement of the two end chambers 11 and 13, of 15 the inlet pipe 20 to the distributing box 15 and of the branch pipes 21 and 23 to the end chambers 11 and 13, is essentially the same as the arrangement of chambers *h* and *i*, box *b*, inlet pipe *a* and branch pipes *c* and *d*, 20 shown in Figs. 1 and 2. The additional, or middle, chamber 12 is arranged at a level below that of chambers 11 and 13 and the branch pipe 22 extends downward in the same vertical plane through which inlet pipe 25 20 extends, this plane bisecting chamber 12 lengthwise and being midway between and parallel to chambers 11 and 13. The junction box 15 is preferably hexagonal in cross-section, comprising two end walls and six sides. 30 Inlet pipe 20 extends into one end wall of the box, and outlet pipes 21, 22 and 23 connect with three of its sides. The box is orificed on the other end wall and the other three sides and in line with respective pipes 20, 21, 22 and 35 23, the orifices being closed by plugs 30, 31, 32 and 33.

Having now fully described my invention, what I claim and desire to protect by Letters Patent is:

40 1. In an oil cracking plant, the combination, with an inlet pipe for highly heated hydrocarbons, of a plurality of reaction chambers, branch pipes communicating respectively with the reaction chambers, and a 45 junction box provided with an inlet communicating with the inlet pipe and outlets communicating with the branch pipes, and removable plugs in the walls of the inlet box respectively opposite the said inlet and outlets. 50

2. In an oil cracking plant, the combination, with an inlet pipe for highly heated hydrocarbons, of a junction box into which said pipe discharges, two horizontal reaction 55 chambers arranged in parallelism on opposite sides of the junction box, and two branch pipes connecting the junction box with the respective chambers, said branch pipes extending at substantially equal angles to, and 60 on opposite sides of, a vertical plane extending between, and parallel to the direction of extension of, the two chambers.

3. In an oil cracking plant, the combination, with an inlet pipe for highly heated hydrocarbons, of a junction box into which said 65

pipe discharges, two horizontal reaction chambers arranged in parallelism on opposite sides of the junction box, and two branch pipes connecting the junction box with the respective chambers, said branch pipes extending at substantially equal angles to, and on opposite sides of, a vertical plane extending between and parallel to the direction of extension of, the two chambers, the end of the inlet pipe communicating with the junction 70 box extending in said plane and substantially bisecting the angle between the two branch pipes. 75

4. In a cracking plant, the combination with a plurality of horizontally extending 80 reaction chambers arranged side by side, of a common supply pipe, branch pipes communicating with the supply pipe and with the respective reaction chambers, outlet pipes for cracked hydrocarbons comprising end 85 sections extending from opposing sides of adjacent reaction chambers obliquely upward at relatively sharp angles to the horizontal and at a relatively wide angle to the vertical, manually regulable valves on said 90 end sections, and boring-out devices connected and aligning with said valved pipe sections.

5. In a cracking plant, the combination with a plurality of horizontally extending 95 reaction chambers arranged side by side, of a common supply pipe, branch pipes communicating with the supply pipe and with the respective reaction chambers, outlet pipes for cracked hydrocarbons comprising end 100 sections extending toward one another along radii of two adjacent tanks above and at acute angles to a horizontal plane intersecting the axes of both tanks and extending also in vertical spaced-apart planes perpendicular 105 to the axes of the tanks, regulable valves on said end pipe sections, and boring-out devices connecting and aligning with said valved end pipe sections.

6. In an oil cracking plant, the combination with a plurality of reaction chambers, of a valveless junction box, an inlet pipe connected with and adapted to convey highly heated hydrocarbons to the junction box, a plurality of valveless pipe sections connecting the junction box with the respective chambers and tending to equally divide the flow of hydrocarbons to the chambers, and means at the outlet end of the reaction chambers to enable the operator to visually ascertain and manually substantially equalize the comparative conditions in the reaction chamber and thereby, without manual regulation of the supply to the respective chambers, insure a substantially equal division of the 115 hydrocarbon supply thereto. 120

7. In an oil cracking plant, the combination with an inlet pipe for highly heated hydrocarbons, of a junction box into which said pipe discharges, two horizontal reaction 125 chambers arranged in parallelism on opposite sides of the junction box, and two branch pipes connecting the junction box with the respective chambers, said branch pipes extending at substantially equal angles to, and 130 on opposite sides of, a vertical plane extending between, and parallel to the direction of extension of, the two chambers.

chambers arranged in parallelism on opposite sides of the junction box, a third horizontal reaction chamber arranged below the junction box and between, and in parallelism with, and below the level of, the other two reaction chambers, and branch pipes connecting the junction box with the respective chambers.

8. In an oil cracking plant, the combination with an inlet pipe for highly heated hydrocarbons, of a junction box into which said pipe discharges, two horizontal reaction chambers arranged in parallelism on opposite sides of the junction box, a third horizontal reaction chamber arranged below the junction box and between, and in parallelism with, and below the level of, the other two reaction chambers, and branch pipes connecting the junction box with the respective chambers, the branch pipe connecting the junction box with the middle chamber extending downward in substantially a vertical plane extending between, and parallel to the direction of extension of, the end chambers, and the other two branch pipes extending at substantially equal angles to, and on opposite sides of said plane.

9. In an oil cracking plant, the combination, with an inlet pipe for highly heated hydrocarbons, of a plurality of reaction chambers, a junction box into which said inlet pipe discharges, and a plurality of pipes radiating from the junction box and communicating with the respective chambers, said box having two end walls and sides equal in number to twice the number of reaction chambers, said inlet pipe discharging into one end wall and the other pipes discharging from side walls, and removable plugs in the walls of the inlet box respectively opposite the walls from which said pipes extend.

10. In an oil cracking plant, the combination, with an inlet pipe for highly treated hydrocarbons, of a junction box into which said pipe discharges, two horizontal reaction chambers arranged in parallelism on opposite sides of the junction box, and two branch pipes connecting the junction box with the respective chambers, said branch pipes extending at substantially equal angles to, and on opposite sides of, a vertical plane extending between, and parallel to the direction of extension of, the two chambers, outlet pipes for cracked hydrocarbons comprising end sections extending from opposing sides of adjacent reaction chambers obliquely upward at relatively sharp angles to the horizontal and at a relatively wide angle to the vertical, and manually regulable valves on the outlet pipes.

11. In a cracking plant, the combination with a plurality of reaction chambers, of a common supply pipe for highly heated hydrocarbons, branch pipes for conducting said hydrocarbons from the supply pipe to the

respective chambers, means tending to equally distribute said hydrocarbons from the supply pipe to the branch pipes, outlet pipes for cracked hydrocarbons from the respective chambers, pressure gauges on the outlet pipes beyond the respective valves for measuring the relative pressure drops and the relative flow through the different outlet pipes, and valves controlling the outlets from the respective tanks to the respective outlet pipes, said valves being manually regulable to re-establish equality of flow through the outlet pipes in case said pressure gauges indicate different pressures.

12. In a cracking plant, the combination with a plurality of reaction chambers, of a common supply pipe for highly heated hydrocarbons, branch pipes for conducting said hydrocarbons from the supply pipe to the respective chambers, means tending to equally distribute said hydrocarbons from the supply pipe to the branch pipe, outlet pipes for cracked hydrocarbons from the respective chambers, manually regulable valves controlling the respective outlets, pressure gauges on the reaction chambers, adapted to indicate the pressures in the respective tanks, pressure gauges on the outlet pipes beyond said pipes adapted to indicate the relative pressure drops and relative flow through said pipes, thereby enabling the operator to so adjust said valves as to establish substantial equality of pressures in the reaction chambers and thus insure substantially equal supplies of hydrocarbons to the chambers by the distributing means.

In testimony of which invention, I have hereunto set my hand, at Marcus Hook, Pa., on this 3d day of June, 1927.

HENRY THOMAS.
